UNITED STATES PATENT OFFICE

HOWARD A. VISEL, OF ELKHART, INDIANA

DESIGN FOR AN ADVERTISING DEVICE OR THE LIKE

Application filed December 30, 1932. Serial No. 46,670. Term of patent 14 years.

To all whom it may concern:

Be it known that I, HOWARD A. VISEL, a citizen of the United States, residing in Elkhart, county of Elkhart, Indiana, have invented a new, original, and ornamental Design for an Advertising Device or the like, of which the following is a specification, reference being had to the accompanying drawing, forming a part thereof, and wherein the

It is intended that my new advertising device shall be disposed of or sold as a single article of manufacture, and that its component parts remain intact, as shown.

I claim:

The ornamental design for an advertising device as shown and described.

HOWARD A. VISEL.
